HAROLD ROUNTREE, OF SCARSDALE, NEW YORK, ASSIGNOR TO NATIONAL PNEUMATIC COMPANY, OF NEW YORK, N. Y., A CORPORATION OF WEST VIRGINIA.

DOOR-OPERATING MEANS.

Application filed November 22, 1924. Serial No. 751,497.

This invention relates to the operation of doors, and, while adapted for general application, is particularly intended for use in connection with the doors of cars and buses, 5 in which environment, it may also serve to operate and control the hinged or folding steps with which cars and buses are frequently provided.

The primary object of the invention is to 10 provide a very simple and compact mechanism for the control and operation of doors, either alone or in conjunction with folding or hinged steps.

When utilized to operate and control a 15 hinged car door and step, the invention may conveniently embody a prime mover in the form of a reversible electrical motor connected with the door and step by gearing connections including a friction clutch through 20 which power is transmitted from the motor to the door and step. With the motor is associated an electric circuit by which the operations of the motor may be controlled to open and close the door and correspondingly move 25 the step. This control circuit includes switch mechanism for reversing the feed of current to the motor and this switch mechanism may be either manually or automatically operated or may be controlled conjointly by an automatic and manual operation. Moreover, I 30 may include in the control circuit means which renders the operation of such circuit dependent upon the stopping of the car. In other words, such means may be so constituted 35 that the operation of the doors cannot take place unless the car is at rest, the purpose of which arrangement is to obviate accidents which are apt to result if persons are permitted to board or leave the car while it is 40 in motion.

Inasmuch as the door is opened and closed through friction drive connections, means is preferably provided for locking a door in its closed position independently of such connections, so that if persons lean or are thrown 45 against the door, the door will not inadvertently open. This means may partake of various forms which, however, in practice, preferably include automatic mechanism for releasing the door when it is desired to open 50 the same through the connections described although emergency manually operable devices are also preferably included to permit the door to be released through a manual op-

eration if such should be desired for any 55 reason.

An important feature of the invention resides in the pronounced simplicity of the structural elements entering into its practical embodiments, and the unfailing manner of its 60 operation.

The structure may be made very compact and such wiring, as is associated therewith and forms part thereof, is relatively simple and lends itself to very efficient control either 65 through purely manual or automatic means or a combination of both.

A further important feature of the invention is found in the simple driving connections between the motor and the door. In 70 practice, these driving connections preferably consist in a worm fixed on the armature shaft of the reversible motor and driving a worm wheel with which a friction disk is rigid. With this friction disk cooperates another 75 disk rigid with the pinion which meshes with a gear segment fixed on the door shaft. A spring serves to force these disks together under elastic pressure and thus renders the door shaft responsive to the operations of the 80 motor. At the same time, the cooperating friction disks form between these parts a yieldable connection which will permit overtravel of the motor after the door is opened or closed without overloading the motor, 85 which might result in burning out the motor or blowing a fuse.

Features of the invention, other than those specified, will be apparent from the herein-after detailed description and claims, when 90 read in conjunction with the accompanying drawings.

The invention consists substantially in the construction, combination, location and relative arrangement of parts, all as will be more 95 fully hereinafter set forth, as shown by the accompanying drawings and finally pointed out in the appended claims.

Figure 1 is a plan view of door operating mechanism embodying the present invention, 100 the same being illustrated as enclosed within a suitable casing, the cover of which is removed in the showing of Figure 1, so that said figure, in effect, corresponds to a section taken on the line 1-1 of Figure 2.

Figure 2 is a section on the line 2-2 of 105 Figure 1 showing certain parts in elevation in the interest of clearness.

Figure 3 is a vertical section taken through the upper portion of a door and through the juxtaposed portion of the door casing and illustrating in section means embodying the present invention for normally locking the door in closed position; and,

Figures 4 and 5 are wiring diagrams showing different ways in which the operation of the mechanism, illustrated in Figures 1 and 2, may be controlled.

In car construction, the folding or hinged doors with which such cars are usually provided are generally mounted on one or more vertical shafts which forms the pivot or pivots of the door or doors, while the step is mounted to pivot on a horizontal axis and is generally connected to the shaft which operates the door in such manner that when the shaft is rotated through an angle of 90 degrees, the door is opened or closed and the step is simultaneously extended or withdrawn. This construction is so well known that it has not been considered necessary to show it in the drawings, so that I have simply illustrated in Figures 1 and 2 one end of the door operating shaft which bears reference character 1.

In accordance with the present invention, I affix to the shaft 1 a gear element 2, and inasmuch as it is the general practice to place the shaft 1 relatively close to a post or some other fixed part of the car structure, I prefer, in the interest of compactness, to make the gear element 2 in the form of a segment, as shown best in Figure 1. This segment is firmly affixed to the shaft and when operated will serve to impart rotation thereto.

3 designates a prime mover by means of which operation of the door is effected and in practice this prime mover is preferably in the form of a small reversible motor of which I preferably employ one of the compound wound type, which will be able to make a rapid start and at the same time will not exceed its rated maximum speed. This motor is mounted within a suitable casing 4, preferably made sufficiently large to also enclose the end of the shaft 1 and the gear segment 2 associated therewith.

On the armature shaft 5 of the motor, a worm 6 is affixed and this worm meshes with a worm wheel 7 mounted to freely rotate on a stub shaft 8 carried by the casing 4, as shown best in Figure 2.

A friction disk 9 is rigid with the worm wheel 7 and is adapted for cooperation with another friction disk 10 rigid with the pinion 11. The pinion 11 and disk 10 are also mounted to freely rotate on the shaft 8 and said shaft is so positioned relative to the shaft 1, that the pinion 11 will mesh with the gear segment 2 on the latter shaft. A spring 12 bears against the worm wheel 7 and forces the disk 9 under elastic pressure against the disk 10 to establish a friction drive connec-

tion between these parts. In this manner, the shaft 1 is made responsive to the operations of the prime mover 3, though it will be understood that the presence of the friction disks will permit overtravel of the motor after the door has been fully opened or closed and will also insure against injury to persons who may be caught by the door. The motor is thus safeguarded against burning out due to overloads and the inconvenient blowing of fuses is moreover obviated.

In Figures 1 and 2, the arrangement has been shown as adapted to operate one door, either of the single hinged type or of the folding type, embodying a plurality of panels, but it will be understood that in practice this arrangement may be duplicated for a plurality of doors or the shaft 1 of one door may be geared or otherwise connected to the like shaft of a corresponding double door, or other modifications, which will suggest themselves to those skilled in the art, may be employed. Other arrangements adaptable for use in this connection will be hereinafter referred to. However, in every case, the invention will remain substantially the same.

The control of the motor 3 may be accomplished in different ways, but very practical means is illustrated diagrammatically in Figures 4 and 5.

In the former of these figures, 13 designates the handle of manually operable switch mechanism, and 6 the motor to be controlled thereby. In the event that several doors are to be controlled from a common point, a number of these motors may be made controllable from the switch handle 13, by merely wiring them in parallel with one another as would be the case if two or three doors of the same car were to be controlled by one conductor or one motorman.

The handle 13 forms part of switch mechanism including two movable contacts 14 and 15, which are rigid with the handle 13, though insulated therefrom and both of which including the handle are movable about the common pivot 16. The contact arm 14 is adapted to be engaged at all times by a brush 17, while the contact arm 15 is engaged by a similar brush 18. Additional fixed contacts 19, 20, 21, 22, 23 and 24 are provided and are adapted to be engaged by the contacts 14 or 15 when the handle 13 is operated in one direction or the other.

It will be apparent that, when the handle 13 is in zero or neutral position shown in Figure 4, none of the last mentioned fixed contacts will be engaged by either of the contact strips 14 and 15. If, however, the handle 13 is moved from its central position to the left, the strip 14 will engage with both the contacts 19 and 20, while the strip 15 will engage with the contact 24.

The motor 6 is shown in Figure 4 as a compound wound motor and is so wired with re-

spect to the contacts which I have described that the following circuits will be completed when the handle 13 is moved to the left as stated; from a source of current supply 25, 6 current will flow through a wire 26 to the brush 17 and through the strip 14 to the contact 20 and thence through a wire 26 to the lower armature brush 27 of the motor. Leaving the armature through the upper brush 28, 10 the current flows through a wire 29 to contact 24, through strip 15 to brush 18 and from brush 18 through wire 30 to the series field 31 of the motor. Leaving the series field, the current passes through the wire 32 to ground 15 at 33. This will cause the motor to operate in one direction, e. g., the direction appropriate to bring about the opening of the door. If, in contradistinction, to the operation previously described, the handle 13 is moved to 20 the right, the following circuits will be completed; from source 25 through wire 26 to brush 17, strip 14, contact 22, cross connection 34, to contact 24, through wire 29 to upper armature brush 28. Through the armature to 25 lower armature brush 27 and by wire 26 to contact 17. Thence through cross connection 35 to contact 23, strip 15, brush 18, and wire 30 to the series field, after which it passes through the return 32 to ground at 33, with 30 the result that the motor is operated in the opposite direction.

When the arm 13 is moved in either direction, as has been described, the motor will operate so long as it is held in either of its 35 terminal positions and said motor will be de-energized or will cease to operate when the handle 13 is returned to neutral position.

It may frequently be desirable in adapting the present invention to the operation and 40 control of car doors, to render the operation of the doors provisional on the stopping of the car, and while this may be accomplished in various ways, one typical form of means which may be employed for this purpose 45 is illustrated in Figure 4 as comprising switch mechanism generally designated by the reference character 36. This switch comprises a bridge piece 37 which, as shown, is pneumatically controlled. It is illustrated as 50 secured to a piston 38 operable within a cylinder 39. A spring 40 normally forces the bridge piece free from contacts 41 and 42 which are included in the wire 26 and thus 55 normally breaks any circuit which might be otherwise made through this wire.

A pipe 43 is connected to the air-brake system of the car, so that when the air is on to actuate the brakes, pressure is admitted to the cylinder 39 and moves the piston 38 to 60 cause the bridge piece 37 to bridge the contacts 41 and 42.

When this arrangement is employed, it will be apparent that the operation of the doors is dependent upon the stopping of the car.

Manifestly, there are many ways in which

power might be applied to control the operations of the bridge piece 37 and while I have shown it as pneumatically operated, it might be electrically operated, or otherwise. The purpose of the switch 36 is to make this 70 circuit inoperative whenever the car controller, or the brakes, or some other essential part of the car operating system, has been so manipulated that it would be no longer desirable for the doors to be operative. In the principal form shown in the drawings, a pneumatic operation is illustrated, but in lieu of the cylinder and piston, I might well employ a magnet or solenoid in which event the contacts 41 very probably 75 should be placed on the other side of the bridge piece member. In lieu of the structure shown, however, the manually operated switch for controlling the doors can have its feed circuit coming through either a contact 80 on the car controller or through a contact operated by the pressure either from the brake pipe system or from the brake controller, so that no doors can be opened when the car is running. Manifestly if desired the starting 85 of the car can also be made to cause any open door to close by a pressure cylinder connected to the brake system, or by a magnet connected to the controller system positively moving the door controlling switch to closing 90 position when the car is started.

In Figure 5, the same general arrangement is shown as is illustrated in Figure 4, but with slight modifications. That is to say, instead of operating the handle 13 manually, it is connected by a link 44 to a bell crank 45 pivoted at 46 and operable by a treadle 47. The far end of the treadle has connected thereto a similar bell crank 45^a and the two bell cranks are connected together by a link 48. A spring 49 normally elevates the treadle and moves the operating handle 13 to one extreme position. When the weight is imposed on the platform, the bell cranks are tilted and act through the link 44 to move the handle 13 to its other extreme position. When this construction is employed a manually operable switch 50 is preferably employed in lieu of the switch 36 of Figure 4.

The switch 50 is placed in a position to be readily accessible to the car attendant and its purpose is to stop the motor from further operation after the door or doors are closed and there are no more passengers to alight 110 and to also make the treadle device inoperative whenever it is desired that it should not be used.

If desired, a switch similar to the switch 36 may be arranged in series with the switch 50 so as to render the motor irresponsive to the operations of either the switch 50 or the treadle operated switch unless the car is at rest.

Inasmuch as the connection between the 130

door operating motor and the door shaft is through a friction device, it might be possible for someone leaning against the door to cause it to open, and to overcome this possibility, I preferably employ a locking device in conjunction with the door and which device is preferably in the form of a latch or detent adapted to latch over the upper edge of the door 51 and so normally retain it in closed position. Different means may be employed to operate this latch and the latch may be of different forms, but Figure 3 of the drawings shows an illustrative construction.

15 In Figure 3, the latch is in the form of a bell crank 52, one arm 53 of which is adapted to engage with the upper portion of the door 51, while the other arm 54 of which projects upwardly and has secured thereto a spring 55 which serves to normally impel the arm 53 into engagement with the door. The latch may be moved in the opposite direction in many different ways, but for the purpose of illustration, the means shown for accomplishing this result is in the form of a piston 56 to which fluid pressure, as from the air brake system, is applied when the car is stopped, with the result that when the car stops the latch is moved away from the door, so that 20 the door can be opened. In lieu of the pneumatically operated piston 56, I may, however, employ electromagnetic means and the power may be transmitted to the latch either to directly raise the latch or the latch can be raised by a spring which is held against action by the power means. In one case, the door will be latched shut, whenever, and as long as, the power means are applied, and in the other case, the door will be latched shut 25 whenever the power means are not applied. As to which of these two methods is used in practice of course depends upon how the operating power is controlled.

If electrical means are employed to actuate 30 the latch, it can be cut on or off simultaneously with the motion of the manually operated switch that controls the door, or with and by the action of an extra segment on the car controller, or with and by the action of 35 the pneumatic switch in conjunction with the air brake or air brake valve. All of these methods are equally applicable for use with this type and in all cases they work to cause the door to be locked shut by a detent whenever, under normal conditions, the door should not be used.

It is important, however, that some means should be provided to permit the unlocking of the latch in the case of emergency or otherwise and in every instance, irrespective of the automatic control of the latch such manual means is embodied.

In the construction shown in Figure 3 of the drawings, the manual means consists of 40 a rod 57 connected to the arm 54 of the latch

and extending into a convenient position to permit it to be operated manually to release the latch and permit the opening of the door. In the event of emergency, the door, after being unlocked, may be forced open by a strong 70 shove because of the friction connection between the door and the motor 3.

In the accompanying drawings, I have shown a connection between the driving motor 3 and the door shaft of one door, but, in practice, many modifications or amplifications of this simple electric power engine can be made. For example, if the ordinary four panel folding door is used, and which includes two vertical shafts, one for each door, there can be a mere duplication of the mechanism shown in Figures 1 and 2, for each of these shafts and the motors can be arranged in parallel in the wiring diagrams of either Figures 4 and 5, so that both motors are controlled simultaneously. Moreover, instead of duplicating the motor arrangement, one motor may be used and the two door shafts connected by a cross connection as is customary in the pneumatic operation of doors. 80 Moreover, if separate electric engines, as shown in Figures 1 and 2, are employed for the entrance and exit doors, the entrance door can be controlled by a manually operated switch, as described and shown in Figure 4, 85 and the exit door can be controlled by a treadle device inside the doorway which, when depressed, completes the circuit of the motor for opening that door, and, when liberated, completes the circuit for closing that door.

In the latter case, the feed connection of the treadle switch which would have to be broken before the motor operated thereby would cease running, can be controlled either by the switch of the entrance door or by an additional contact on the car controller or by a switch operated by pneumatic pressure from the air pipe valve or from the air brake controller as will be apparent from the foregoing description, so that when the motorman had either started the car or was prepared to start the car, the exit door could no longer be opened.

I have described the step as mechanically connected in any suitable and well known manner to the shaft on which the associated door is mounted, but, in practice, an independent motor, constructed as shown in Figures 1 and 2, might be employed to operate 110 the step independently without departing from this invention.

While I have shown and described various structures and arrangements embodying the principle of my invention, I wish it to be understood that my broad invention, as defined in the claims, is not limited or restricted to any specific arrangement or to any detail thereof, as it is obvious that many modifications and changes in detail will readily occur 125 130

to those skilled in the art without departing from the spirit of my invention.

Therefore, having now set forth the objects and nature of my invention, and having shown and described an operative structure embodying the principles thereof, what I claim as new and of my own invention, and desire to secure by Letters Patent is:

1. In an electric engine for operating a hinged car door, the combination with an electric motor, a worm associated with the armature thereof, a worm wheel meshing with said worm and positively driven thereby, and a friction disk rigid with respect to said worm wheel, of a door shaft, a gear fixed thereon, a pinion meshing with said gear, a friction disk rigid with the pinion, and means for maintaining said friction disks in engagement under elastic pressure.

2. In an electric engine for operating a hinged car door, the combination with an electric motor, a worm associated with the armature thereof, a worm wheel meshing with said worm and positively driven thereby, and a friction disk rigid with respect to said worm wheel, of a door shaft, a gear segment fixed thereon, a pinion meshing with said gear segment, a friction disk rigid with the pinion, and means for maintaining said friction disks in engagement under elastic pressure.

3. In door operating apparatus of a car, the combination with an engine operatively connected to the door and including, as a prime mover, a reversible electric motor, of means for controlling the operations of said motor in either direction, and means for rendering the operations of the motor dependent upon the stopping of the associated car.

4. In operating apparatus for hinged and folding doors, the combination with a door operating engine comprising a reversible electric motor operatively connected to an associated door through friction drive connections, of current switching means for controlling the direction of feed of current to the motor to thereby control the direction of operation of the motor, and automatically operated switching means for rendering the

motor inoperative except at predetermined times.

5. In door operating apparatus of a car, the combination with a door, of a prime mover, operative connections, including friction drive means between the prime mover and door, and pneumatically operated means adapted to lock the door against the operation of the prime mover while the brakes of the associated car are inoperative.

6. In door operating apparatus of a car, the combination with a door, of a prime mover, operative connections, including friction drive means between the prime mover and door, means adapted to automatically lock the door against the operation of the prime mover, while the brakes of the associated car are not in operation, and manually operable means adapted when manually actuated to release the door at any time.

7. In an electric engine for operating a car door, the combination with a casing provided with an opening through which a door shaft is adapted to project into the casing, a bearing associated with said opening and shaft to mount the shaft for rotation in the opening, a door operating element adapted to be secured to the shaft within the casing, an electric motor positioned within the casing, bearings formed in the casing for supporting the armature shaft of the motor for rotation, a worm fixed on the armature shaft, a stub shaft positioned within and rigid with the casing, a worm wheel mounted to rotate freely on the stub shaft while in mesh with the worm, a friction disk associated with said worm wheel, a pinion meshing with the door operating element and mounted to freely rotate on the stub shaft, a friction disk rigid with the pinion, and means for maintaining said friction disks in engagement under elastic pressure to afford a yieldable driving connection between the motor and the door operating element.

In testimony whereof I have hereunto set my hand on this 18th day of November, A. D. 1924.

HAROLD ROWNTREE.
